A. MORIN

SHADE BRACKET

Filed Nov. 1, 1927

Patented Dec. 18, 1928.

1,696,050

UNITED STATES PATENT OFFICE.

ADELARD MORIN, OF NASHUA, NEW HAMPSHIRE.

SHADE BRACKET.

Application filed November 1, 1927. Serial No. 230,282.

This invention relates to a bracket designed primarily for supporting window shades, but it is to be understood that it may be employed for any purposes for which 5 it is found applicable, and the invention has for its object to provide, in a manner as hereinafter set forth, a supporting bracket including means for detachably clamping it in supporting position to a window frame 10 without the employment of separate hold-fast devices, such as nails and screws, whereby the frame is not damaged or marred in any manner.

A further object of the invention is to 15 provide, in a manner as hereinafter set forth, a window shade bracket constructed and arranged to provide for the expeditious clamping thereof to a window frame in position to support a shade roller and without 20 the employment of nails and screws to maintain the bracket in supporting position.

A further object of the invention is to provide, in a manner as hereinafter set forth, 25 a bracket for supporting a shade roller constructed and arranged to fit different widths of top rails, bars or members of window frames.

Further objects of the invention are to 30 provide, in a manner as hereinafter set forth, a shade roller supporting bracket which is simple in its construction and arrangement, strong, durable, compact, lengthwise adjustable, thoroughly efficient in its use, expeditiously secured to the top of a window frame without the employment of 35 nails and screws, and comparatively inexpensive to manufacture.

With the foregoing and other objects in 40 view the invention consists of the novel construction, combination and arrangement of parts as hereinafter more specifically described, and illustrated in the accompanying drawings, wherein is shown an embodiment 45 of the invention, but it is to be understood that changes, variations and modifications can be resorted to which fall within the scope of the claims hereunto appended.

In the drawings wherein like reference 50 characters denote corresponding parts throughout the several views:-

Figure 1 is a fragmentary view, in front elevation, of a window frame, showing the adaptation therewith of a pair of support-

ing brackets in accordance with this invention and with the brackets supporting a shade roller and a curtain pole.

Figure 2 is a side elevation of a bracket showing the adaptation thereof with respect to the top of the window frame.

Figure 3 is a rear elevation of the bracket.

Figure 4 is a vertical sectional view of the bracket and with the same clamped to the window frame.

Figure 4^a is a section on line 4^a—4^a Figure 3.

Figure 5 is a section on line 5—5. Figure 3.

Figure 6 is a detail section of the lower 70 part of the bracket.

Figure 7 is a detail section of the upper 75 part of the bracket.

Referring to the drawings 1 indicates a top rail, bar or member of a window frame 2 and which has clamped therewith, in spaced relation, a pair of supporting brackets, in accordance with this invention, and which are generally indicated at 3, 4. Supported by the brackets 3, 4 is a curtain pole 5 and a shade and its winding roller indicated at 6. The pintles of the shade roller are mounted in the arms 7, 8 respectively of the brackets 3, 4 and the pinte mounted in the arm 7 is indicated at 9 and that mounted in the arm 8 at 10. The arm 7 is provided with an opening 11 for the pinte 9 and the arm 8 with a slot 12 for the reception of the pinte 10. The brackets 3, 4 are provided with angle shaped arms 13, 14 respectively for supporting the pole 5. The brackets 3, 4 are of like construction, with this exception that the arm 7 which projects from the bracket 3 is provided with an opening 11 and the arm 8 which projects from the bracket 4 is provided with a slot 12. Otherwise than as stated the brackets are of like construction and but one will be described, as the description of one will apply to the other.

Each of the brackets includes a body portion formed of a pair of telescopic sections 15, 16 of channel shaped cross section. The section 15 is the outer one and the section 16 the inner. The outer section 15 comprises a front 17, a top 18 and a pair of sides 19, 20. The width of the top 18 is greater than the width of either of the sides whereby the top 18 will project rearwardly from the

upper ends of the sides. The rear of the top 18 is formed with a toothed flange 20 which is parallel with the front 17 and forms a clamping member for extension into the top edge of the bar 1 to secure the section 15 in position. See Figure 4. The top edges of the sides 19, 20 are not integral with the top 18, and the latter can be secured to the sides 19, 20 by flexible tie members 22 which extend through openings 23 formed in said top and sides. See Figure 7. The tie members 22 can be dispensed with if desired. The side 20 is slotted at two spaced points, transversely thereof, as 15 at 24 and the material freed by said slits and which is indicated at 25 is bent to seat against the outer face of the front 17 and formed integral with said portion 25 is a forwardly directed extension 26 which provides the arm 7 or 8. The width of the portion 25 corresponds to half of the width of the front 17 whereby the extension 26 will be disposed at the vertical median of said front 17. That part of the side 20, other 20 than the portion 25 thereof, at its rear is formed with an inwardly extending angle shaped flange 27 providing a guide. The rear of the side 19 is formed with an inwardly extending angle shaped flange 28 which 25 also provides a guide. The guides 27 and 28 receive the sides of the section 16, guiding the latter during its movements as well as slidably connecting it to the section 15.

The section 16 comprises a front 29, a bottom 30 and a pair of sides 31, 32. The width of the bottom 30 is greater than the width of either of the sides whereby said bottom will project from the rear of said sides. The width of the bottom 30 is greater 35 than the width of the sides of the section 15. The rear of the bottom 30 is formed with a toothed flange 33 parallel with the inner face of the front 29 and it provides a clamping member for securing the section 16 in position and it is adapted to extend into the bar 1, at the bottom edge thereof. See Figure 4. The sides 31 and 32, at their lower ends, are connected to the bottom 30 by bendable lugs 34 carried by said sides 40 and extending through openings 35 formed in the bottom 30. See Figure 6.

Secured to the front 17 of the section 15, as well as projecting forwardly thereof and arranged a substantial distance above the 45 extension 26 is an angle shaped member 35 which provides the arm 13 or 14. The member 35 has its inner end upset as at 36 against the inner face of the front 17. The top edge of the front 29, of the section 16 50 is formed with a notch 37 to provide a clearance for the upset portion 36 of the member 35.

The sections 15 and 16 are normally maintained in non-extended position, due to the 55 action of a coiled controlling spring 38

which has one end anchored to the top 18 of the section 15, as at 39 and its other end anchored to the bottom 30, of the section 16 as at 40. The sections of the body portion are extended against the action of the controlling spring 38 and said spring 38 acts to maintain the toothed flanges in engagement with the top and bottom edges of the bar 1.

When positioning the bracket the sections of the body portion are extended in a manner such that the top of the section 15 will overlap the top edge of the bar 1 and the bottom of the section 16 will overlap the lower edge of the bar 1 and when the sections are released, the controlling spring 38 will act to cause the toothed flanges to extend into the bar 1 whereby the bracket will be detachably secured in position. The springs 38 will permanently act, to clamp, in connection with the toothed flanges, the bracket to the bar 1 of the window frame. The bracket is secured in position, to the window frame, without the employment of holdfast devices, such as nails and screws, and under such conditions the front of the top of the frame is not marred or damaged in any manner. As the body portion is formed with a pair of telescopic sections, it can be adjusted to fit top bars of window frames of varying widths.

It is thought the many advantages of a shade supporting bracket, in accordance with this invention can be readily understood, and although the preferred embodiment of the invention is as illustrated and described, yet it is to be understood that changes in the details of construction can be had which fall within the scope of the invention as claimed.

What I claim is:

1. In a supporting bracket for the purpose set forth comprising a lengthwise adjustable body portion formed of inner and outer slidably connected telescopic sections of channel shaped cross section, the outer section closed at its top and the inner section closed at its bottom, a controlling spring common to said sections, arranged therein and having one end anchored to said top and its other end anchored to said bottom, said outer section having its top formed with a toothed flange to provide a clamping member, said inner section having its bottom formed with a toothed flange providing a clamping member, said flanges extending inwardly at right angles with respect to said top and bottom, and a forwardly extending supporting arm carried by said outer section.

2. A supporting bracket for the purpose set forth comprising a lengthwise adjustable body portion formed of inner and outer slidably connected telescopic sections of channel shaped cross section, the outer section closed at its top and the inner section

- closed at its bottom, a controlling spring common to said sections, arranged therein and having one end anchored to said top and its other end anchored to said bottom, 5 said outer section having its top formed with a toothed flange to provide a clamping member, said inner section having its bottom formed with a toothed flange providing a clamping member, said flanges extending inwardly at right angles with respect to said top and bottom, and a forwardly extending supporting arm carried by said outer section, said arm integral with said outer section and disposed at the vertical median thereof. 10
- 15 3. A supporting bracket for the purpose set forth comprising a lengthwise adjustable body portion formed of inner and outer slidably connected telescopic sections of channel shaped cross section, the outer section closed at its top and the inner section closed at its bottom, a controlling spring common to said sections, arranged therein and having one end anchored to said top and its other end anchored to said bottom, said outer section having its top formed with a toothed flange to provide a clamping member, said inner section having its bottom formed with a toothed flange providing a clamping member, said flanges extending inwardly at right angles with respect to said top and bottom, and a forwardly extending supporting arm carried by said outer section, said arm integral with said outer section and disposed at the vertical median thereof. 20
- 25 4. A supporting bracket for the purpose set forth comprising a lengthwise adjustable body portion formed of inner and outer slidably connected telescopic sections, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting rearwardly therefrom, the bottom of the inner section being of greater width than the sides thereof and projecting 70 rearwardly therefrom, a controlling spring arranged in said sections and having one end anchored to said top and its other end anchored to said bottom, inwardly extending right angularly disposed flanges carried by said top and bottom and providing clamping members for said body portion, and an arm projecting forwardly from the front of said outer section, said arm integral with said outer section and disposed at the 75 vertical median thereof. 80
- 30 5. A supporting bracket for the purpose set forth comprising a lengthwise adjustable body portion formed of inner and outer slidably connected telescopic sections, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting 85 rearwardly therefrom, the bottom of the inner section being of greater width than the sides thereof and projecting rearwardly therefrom, a controlling spring arranged in said sections and having one end anchored to said top and its other end anchored to said bottom, inwardly extending right angularly disposed flanges carried by said top and bottom and providing clamping members for said body portion, and an arm projecting forwardly from the front of said outer section, said arm integral with said outer section and disposed at the 90 vertical median thereof. 95
- 35 6. A supporting bracket for the purpose set forth comprising a lengthwise adjustable body portion formed of inner and outer slidably connected telescopic sections, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting 100 rearwardly therefrom, the bottom of the inner section being of greater width than the sides thereof and projecting rearwardly therefrom, a controlling spring arranged in said sections and having one end anchored to said top and its other end anchored to said bottom, inwardly extending right angularly disposed flanges carried by said top and bottom and providing clamping members for said body portion, and an arm projecting forwardly from the front of said outer section, said arm coupled with a side of said outer section and disposed at the vertical median of the latter. 105
- 40 7. A supporting bracket for the purpose set forth comprising a lengthwise adjustable body portion formed of inner and outer slidably connected telescopic sections of channel shaped cross section, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting 110 rearwardly therefrom, the bottom of the inner section being of greater width than the sides thereof and projecting rearwardly therefrom, a controlling spring common to said sections, arranged therein and having one end anchored to said top and its other end to said bottom, said outer section having its top formed with a toothed flange to provide a clamping member, said inner section having its bottom formed with a toothed flange providing a clamping member, said flanges extending inwardly at right angles with respect to said top and bottom, a forwardly extending supporting arm carried by said outer section, and a controlling spring mounted in said body portion and having one end anchored 115 120
- 45 8. A supporting bracket for the purpose set forth comprising a lengthwise adjustable body portion formed of inner and outer slidably connected telescopic sections, the outer section closed at its top and the inner section closed at its bottom, a controlling spring common to said sections, arranged therein and having one end anchored to said top and its other end to said bottom, said outer section having its top formed with a toothed flange to provide a clamping member, said inner section having its bottom formed with a toothed flange providing a clamping member, said flanges extending inwardly at right angles with respect to said top and bottom, a forwardly extending supporting arm carried by said outer section, and a controlling spring mounted in said body portion and having one end anchored 125 130
- 50 9. A supporting bracket for the purpose set forth comprising a lengthwise adjustable body portion formed of inner and outer slidably connected telescopic sections, said outer section having its top formed with a toothed flange to provide a clamping member, said inner section having its bottom formed with a toothed flange providing a clamping member, said flanges extending inwardly at right angles with respect to said top and bottom, a forwardly extending supporting arm carried by said outer section, and a controlling spring mounted in said body portion and having one end anchored

to the top of the outer section and its other end anchored to the bottom of the inner section of said body portion.

8. A supporting bracket for the purpose set forth comprising a lengthwise adjustable body portion formed of inner and outer slidably connected telescopic sections, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting rearwardly therefrom, the bottom of the inner section being of greater width than the sides thereof and projecting rearwardly therefrom, a controlling spring arranged in said sections and having one end anchored to said top and its other end anchored to said bottom, inwardly extending right angularly disposed flanges carried by said top and bottom and providing clamping members for said body portion, an arm projecting forwardly from the front of said outer section, and a controlling spring mounted in said body portion and having one end anchored to the top of the outer section and its other end anchored to the bottom of the inner section of said body portion.

9. A supporting bracket for the purpose set forth comprising a lengthwise adjustable body portion formed of inner and outer slidably connected telescopic sections, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting rearwardly therefrom, the bottom of the inner section being of greater width than the sides thereof and projecting rearwardly therefrom, a controlling spring common to said sections, arranged therein and having one end anchored to said top and its other end anchored to said bottom, inwardly extending right angularly disposed flanges carried by said top and bottom and providing clamping members for said body portion, and one of the sides of said outer section having a pair of spaced slits, the

material freed by the slits positioned against the top of said outer section and terminating in a forwardly directed arm for supporting a shade roller pintle.

10. A supporting bracket for the purpose set forth comprising a lengthwise adjustable body portion formed of inner and outer slidably connected telescopic sections, said outer section formed of a front, a pair of sides and a top, said inner section formed of a front, a bottom and a pair of sides, the sides of said outer section formed with means to provide guides for the sides of the inner section, the top of the outer section being of greater width than the sides thereof and projecting rearwardly therefrom, the bottom of the inner section being of greater width than the sides thereof and projecting rearwardly therefrom, a controlling spring common to said sections and having one end anchored to said top and the other end anchored to said bottom and arranged within said sections, inwardly extending right angularly disposed flanges carried by said top and bottom and providing clamping members for said body portion, and a supporting arm projecting forwardly from the front of said outer section.

11. A supporting bracket for the purpose set forth comprising a lengthwise adjustable body portion formed of inner and outer slidably connected telescopic sections, each of said sections including a front and a pair of sides, said outer section formed of a front and said inner section with a bottom, the sides of one of said sections formed with means to provide guides for the sides of the other of said sections, the tops and bottoms of said sections being of greater width than the sides thereof and projecting rearwardly therefrom, a controlling spring common to said sections, arranged therein and having one end anchored to said top and its other end anchored to said bottom, inwardly extending right angularly disposed toothed flanges carried by said top and bottom and providing clamping members for said body portion, and a supporting arm projecting forwardly from the front of said outer section.

In testimony whereof, I affix my signature hereto.

ADELARD MORIN.
